ADJUSTABLE WALKING AID

Filed Feb. 14, 1946

UNITED STATES PATENT OFFICE

2,474,722

ADJUSTABLE WALKING AID

Herbert E. Blume, Tripoli, Iowa

Application February 14, 1946, Serial No. 647,616

2 Claims. (Cl. 135—50)

1

This invention relates to new and useful improvements and structural refinements in walking aids and applies particularly to the construction of crutches, walking sticks and the like, the principal object of the invention being to provide a device of the character herein described in which such crutches or walking sticks may be adjusted to conform to the various physical requirements of persons employing the same.

It is well-known that many persons who are physically handicapped find it impossible or extremely difficult to ascend or descend stairs, chiefly due to the fact that conventional crutches will not reach one step while the person using the same is standing on another. Such persons are thus unable to support themselves in a substantially erect position and their difficulty in ascending or descending the stairs becomes clearly obvious.

It is therefore, a further object of the invention to provide a walking aid which may be adjusted to compensate for the difference in level between the steps, thereby permitting the persons using the same to support themselves in a substantially erect position.

Another object of the invention is to provide a walking aid which, in addition to the adjustment already described, may also be adjusted to compensate for the physical differences of various individuals, where more than one person are using the same walking aid.

An additional object of the invention is to provide a walking aid which may be easily, conveniently and quickly adjusted, particularly in the event of ascending or descending stairs, when such adjustment may be made without the necessity of the user removing his hand from the hand grip.

A further object of the invention is to provide a walking aid in which a visible means is provided to indicate to the user that the crutch or the like, has been properly adjusted and is in readiness for safe use.

A still further object of the invention is to provide a walking aid which is of simple construction and which cannot easily become damaged.

With the above more important objects in view, and such other objects as may become apparent as this specification proceeds, the invention consists essentially of the arrangement and construction of parts as illustrated in the accompanying drawings, in which:

Figure 1 is a side elevation of the invention.

Figure 2 is a fragmentary, enlarged detail 55 cross-sectional configuration and is provided with

2

thereof, the same being partially broken away to reveal its construction.

Figure 3 is a cross-sectional detail, illustrating the manner in which the leg portion is secured to the crutch.

Figure 4 is a side elevation, showing the leg standard per se, and

Figure 5 is a side elevation illustrating a modified embodiment of the invention, as applied to a walking stick.

Like characters of reference are used to designate like parts in the specification and throughout the several views.

Referring now to the accompanying drawings in detail, the invention consists of a pair of tubular side members 10, the same being relatively parallel and connected together at the upper ends thereof by means of an arcuate strap 10'. This strap is welded or otherwise secured to the side members and is adapted to support a conventional arm rest 11, the latter being attached to the strap by suitable bolts 11'.

Each of the side members 10 is provided medially of its length with a plurality of vertically aligned ridges 12, and a transversely extending hand grip 13 connects the two side members as will be clearly apparent from the accompanying drawings. The grip 13 is provided at each end thereof with a releasable clamp 14, which is secured thereto by means of the bolts 15.

A pair of tubular extensions 16 are telescoped and relatively slidably in the lower ends of the members 10, the lower ends of the extensions being inserted into the upper end of the leg portion 17.

The latter assumes the form of a pair of convergent tubes 18, connected together adjacent their upper ends by means of the brace 19, the ends of the extensions 16 being secured in the tubes 18 by means of suitable, transversely extending rivets 20.

A tubular sleeve 21 is provided at the convergent end of the portion 17 and a leg standard 22 is slidably positioned in the sleeve 21, as will be clearly apparent from the accompanying drawings.

The standard 22 is formed with a plurality of vertically aligned apertures 23 and a transversely extending bolt 24 passes through the sleeve 21 and through one of the apertures 23 to secure the standard 22 in position.

A transverse tie rod 25, positioned below and adjacent to the hand grip 13, connects the members 10. This tie rod is of an inverted, U-shaped

a plurality of aligned bearing blocks 26 and with a pair of slots 27. A pair of anchor bolts 28 are slidably positioned in the blocks 26, each of the bolts extending through an aperture 29 formed in the members 10 and projecting into one of a plurality of vertically aligned apertures 30 provided in the extensions 16.

Each of the bolts 28 is also provided with a transversely extending pin 31, one end of each of these pins projecting through the aforementioned slots 27. A compression spring 32 is positioned between each of the pins 31 and the blocks 26, whereby the bolts 28 are urged outwardly into the apertures 30.

The inner ends of the bolts 28 are angulated downwardly and terminate in the bevelled surfaces or extremities 33. The latter are slidably engageable with the inclined inner surfaces 34 of a triangular pocket 35. This pocket in turn, is connected to a stem 36 which extends upwardly and is slidably journaled in the boss 37 provided on the tie rod 25. The upper end of the stem 36 is threaded into one end of the nut 38 and a T-shaped handle 39 is threaded into the remaining end of the nut, as is best illustrated in the accompanying Figure 2.

A compression spring 40 is positioned on the stem 36 between the boss 37 and the pocket 35, said spring urging the pocket downwardly and thereby assisting the aforementioned springs 32 in urging the bolts 28 into the apertures 30. A suitable pin 41 extends transversely through the stem 36 to limit the sliding movement thereof under the resiliency of the spring 40.

It should be understood that while the stem 36 is freely slidable, axial rotation thereof is not desired and is prevented by forming a portion of the stem and the bore in the boss 37 of a square, rather than of a circular cross-sectional configuration.

Having thus described the constructional details of the invention, its method of operation will now be presented.

The relative position of the hand grip 13 with respect to the side members 10 should first be adjusted to suit the arm length of the individual wishing to use the crutch. This adjustment is accomplished by loosening the bolts 15, whereupon the clamps 14 and the associated grip 13 may be moved upwardly or downwardly on the members 10 to engage any suitable pair of the ridges 12. The grip 13 is retained in a suitably adjusted position by tightening the bolts 15.

The adjustment of the leg standard 22 should next be made, the same being accomplished by removing the bolt 24 and sliding the standard upwardly or downwardly in the sleeve 21 and reinserting the bolt 24 into one of the apertures 23 when a suitable position of the standard 22 has been found. It should be noted in this connection that this adjustment is particularly adapted for use when several individuals are employing the same crutch. When only one person is using the same, the standard 22 may be formed integrally with or otherwise suitably and permanently secured to the tubes 18, since a longitudinal adjustment of the standard will not be necessary.

The crutch is now in readiness for use in normal walking on level ground and when it is desired to ascend or descend stairs, the user will simply pull the handle 39 upwardly whereby the contacting surfaces 33 and 34 will draw the bolts 28 inwardly, that is out of the apertures 30. The

members 10 may now be adjusted upwardly or downwardly on the extensions 16 and when the next pair of apertures 30 is brought into alignment with the anchoring bolts 28, the springs 32 will force the bolts into said apertures and thereby lock the members 10 and the extensions 16 in position. The spring 40 will return the pocket 35 and the associated handle 39 to its original position, whereupon the crutch is in readiness for use.

When ascending or descending stairs, the extensions 16 may be extended outwardly so as to increase the over-all length of the crutch. In this manner, the person using the same is able to support himself in an erect position on one step while bearing with the extended crutch on another step at a relatively lower level. Alternatively, the extensions 16 may be adjusted to an indrawn position in the members 10 so as to shorten the over-all length of the crutch and enable such person to stand on one step and bear with the crutch on another step at a relatively higher level.

It will be observed that in this manner, the task of ascending or descending stairs becomes comparatively simple and the adjustment of the crutch may be easily and conveniently made before and after each time the stairs are used.

It should be also noted that the position of the handle 39 is such that it may be conveniently manipulated without the necessity of the person releasing his hand from the grip 13. Furthermore, by unscrewing the handle 39 from the nut 38 and substituting said handle by another having a comparatively longer or shorter stem, the handle 39 may be brought closer to or further from the hand grip 13, to suit the best convenience of the user.

Referring now to the modified embodiment of the invention illustrated in the accompanying Figure 5, the latter substitutes a walking stick in place of the aforementioned crutch.

This stick assumes the form of a handle 42 positioned in one end of a tubular casing or member 43, while a suitable extension leg 44 is slidably positioned in the remaining end of said member.

The upper end of the leg extension 44 is formed with a plurality of vertically aligned apertures similar to the aforementioned apertures 30, any one of which may be engaged by a slideable anchor bolt 45. The latter is similar to the aforementioned bolts 28 and is suitably journaled in a bracket 46 provided on the member 43. A compression spring 47 is used to urge the bolt 45 into the apertures in the leg 44.

The outer end of the bolt 45 is angulated and bevelled to engage the inclined inner surface of a pocket 48, the latter in turn, being connected to a stem 49 provided with the finger piece or handle 50. The upper end of the stem 49 is freely slidable in a bracket 51, projecting laterally from the member 43.

When this embodiment of the invention is placed in use, the walking stick is employed in the manner already described in connection with the aforementioned crutch by pulling upwardly on the finger piece 50 to withdraw the bolt 45 from the apertures in the leg 44. Thereupon, the over-all length of the stick may be adjusted, and when proper adjustment has been made, the spring 47 will again urge the bolt 45 into a suitable aperture, thus locking the member 43 and the leg 44 in position.

Referring once again to the crutch embodied

ment of the invention, it will be observed that the position of the pins 31 in the recess 27 is directly related to the extent to which the bolts 28 project into the apertures 30. In this manner, the pins 31 may be used to indicate to the person using the crutch that proper adjustment has been made and that such crutch is in readiness for safe usage. If desired, the pins may be 10 luminously colored, whereby their position may be readily ascertained when the crutch is being used at night.

While in the foregoing there has been shown and described the preferred embodiment of this invention it is to be understood that minor changes in the details of construction, combination and arrangement of parts may be resorted to without departing from the spirit and scope of the invention as claimed.

What I claim as my invention is:

1. In an adjustable walking aid including a 20 tubular member and an extension slidably telescoped therein, means for releasably locking said extension in said member, said means comprising a laterally projecting bracket provided on said member, a spring-pressed anchor bolt slidable on said bracket and engageable with apertures formed in said member and in said extension, said bolt having an angulated portion terminating in a bevelled end surface, a vertical stem slideable in said bracket, and a substantially triangular pocket provided on said stem, said pocket having an inclined inner surface in operative en-

gagement with the bevelled end surface of said bolt.

5 2. In an adjustable walking aid including a pair of spaced members and a pair of extensions 15 slidably telescoped therein, means for releasably locking said extensions in said members, said means comprising a transverse tie rod connecting said members together, a pair of spring-pressed anchor bolts slideable on said tie rod and engageable with apertures formed in said members and in said extensions, said bolts having angulated portions terminating in bevelled end surfaces, a vertical handle slideable in said tie rod, and a substantially triangular pocket provided on said handle, said pocket having inclined inner surfaces in operative engagement with the bevelled end surfaces of said bolts.
